FIG. 1

FIG.2

FIG. 1 is a perspective view of a tire for a vehicle wheel showing my new design, it being understood that the tread pattern is repeated throughout the circumference of the tire as shown schematically in solid lines, the opposite side being substantially the same as that shown.

FIG. 2 is an enlarged plan view of the tread pattern thereof.

I claim:

The ornamental design for a tire for a vehicle wheel, as shown and described.
